MEANS FOR PRESSING THE BOTTOMS
OF SHOESCharles H. Pepin, Beverly, Mass., assignor to
United Shoe Machinery Corporation, Paterson,
N. J., a corporation of New JerseyApplication May 23, 1935, Serial No. 23,053
In Great Britain April 3, 1935

18 Claims. (Cl. 12—51)

This invention relates to means for pressing the bottoms of shoes, and more particularly to means for applying pressure and preferably also heat to the lasted margin of an upper overlying an insole to prepare the shoe better for the reception of an outsole, as is a frequent practice in the manufacture of some kinds of shoes. The invention is herein illustrated as applied to pressing means of the same general character as disclosed in a copending application of C. W. Greene, Serial No. 22,051, filed on May 17, 1935, comprising a pressing device or unit for engaging the bottom of the forepart of a shoe and a toe rest movable to press the shoe upon the device, the pressing means being incorporated in a bed-lasting machine; but it is to be understood that in its more general aspects the invention is not limited to a construction of that character or to means which is part of a lasting machine.

An object of the invention is to afford increased insurance under all conditions against any undesirable loosening of the lasted upper at the edge of the toe end of the insole by the pressure applied to the margin of the upper on the bottom of the insole. For the purpose in view, the construction herein shown comprises means which by engagement with the heel end of the shoe not only prevents any displacement of the shoe lengthwise in a heelward direction in the pressing operation, but also imparts to the shoe a short toward movement along the pressing device so that the device has an inward wiping action on the margin of the toe end of the upper. More particularly, in the illustrated embodiment of the invention a heel rest engaging the heel-end face of the shoe is operated to impart such toward movement to the shoe by mechanism which is itself operated by a movement of the pressing device or unit resulting from the pressure of the shoe thereon. To facilitate the movement of the shoe by the heel rest, the toe rest is so mounted as to permit it to move with the shoe. In order that the shoe may be readily presented by the operator in position for the pressing operation, the heel rest in the construction shown is further so controlled that it occupies initially a position comparatively remote from the shoe and is movable by the operator to a position determined by the shoe, after which it is operated as above described.

As disclosed in the above-mentioned copending application, the pressing device herein shown comprises a plate which is flexibly conformable to the contour of the bottom of the toe and ball portions of the shoe in response to pressure of

the shoe thereon. In order to increase the pressure on the margin of the toe end of the upper as compared with the pressure applied at the ball portion of the shoe, the present invention provides an additional flexible plate arranged to reinforce the above-mentioned plate opposite the toe portion only of the shoe.

The above and other features of the invention, including various novel details of construction and combinations of parts, will now be more particularly described by reference to the accompanying drawings and pointed out in the claims.

In the drawings,

Fig. 1 is a view in front elevation of a portion of a bed-lasting machine provided with pressing means constructed in accordance with the present invention;

Fig. 2 is a plan view of the pressing means, illustrating the position of a shoe in relation thereto;

Fig. 3 shows the pressing means partly in left-hand side elevation and partly in section, and illustrates the positions of the parts prior to the application of any substantial pressure to the shoe;

Fig. 4 is a plan view mainly of the bottom-pressing device or unit, with parts broken away;

Fig. 5 is a sectional view similar to a portion of Fig. 3, but illustrating the positions of the parts with the shoe under pressure;

Fig. 6 is a plan view of a portion of the toe rest and a portion of its supporting means, with parts broken away;

Fig. 7 shows a portion of the pressing means in rear elevation;

Fig. 8 is a sectional view of the shoe and the main bottom-pressing plate, as the plate appears with the shoe under pressure; and

Fig. 9 is a perspective view showing the bottom of the forepart of the shoe after it has been operated upon by the pressing means.

Similarly to the disclosure of the above-mentioned copending application, the shoe-pressing means is herein shown as incorporated in a bed-lasting machine of a well-known type, characteristic features of which, relating especially to the lasting of the toe end of a shoe, are described in detail, for example, in United States Letters Patent No. 1,284,870, granted on November 12, 1918 upon an application of Matthias Brock. The construction of parts of the machine other than the shoe-pressing means will therefore be referred to only very briefly. The shoe is supported for the lasting operation on a spindle 10 which enters the spindle hole in the heel end of the last and on a

toe rest 12, and its heel end is engaged and clamped by a heel band 14. For wiping the toe end of the upper heightwise of the last and inwardly over an insole on the last there are provided toe-embracing wipers, a portion of one of which is shown at 16, these wipers being advanced and closed by a hand lever 18. Controlled by the same hand lever is a toe band 20 which embraces and clamps the upper around the toe end 10 of the last, this toe band, however, being sometimes omitted. The wipers and the toe band are supported on a vertically movable slide 22 connected by a link 24 to a double-acting treadle 26 by the use of which the operator raises the wipers 15 to wipe the upper upwardly and also forces them down upon the shoe bottom during or after their inward wiping movements.

For applying pressure and heat to the margin of the forepart of the lasted upper, there is supported on a frame member 28 of the machine, in a location somewhat higher and farther rearwardly than the position occupied by the shoe in the lasting operation but within convenient reach of the operator in his normal working position in front 25 of the machine, a bottom-pressing device or unit 29 generally similar to the device shown in the above-mentioned copending application, the device being mounted in a manner hereinafter described on a bracket 30 fast on the member 28. The pressing device 29 comprises a casting 32 on which there is secured a substantially rectangular hollow casting 34 which serves as a holder for a group of loose metal balls 36 supported underneath by means hereinafter described. These 35 balls, some only of which are shown in Figs. 3 and 5, are confined laterally in part by the walls of the casting 34 and in part by a row of parallel pins 38 slidingly mounted in the casting and arranged to extend all the way around the upper portion of the group of balls, the pins being near enough together to prevent escape of any of the balls. The pins 38 are pressed upwardly by springs 40 which engage enlarged heads 42 on their lower ends, these heads serving by engagement with the casting 34 to limit upward movements of the pins. Supported loosely at its margin on the upper ends of the pins 38 is a thin flexible resilient metal plate 44 arranged to engage the margin of the upper overlying the forepart of the insole, this 50 plate being loosely confined above by a rim 46 secured to the casting 34. This rim is so formed as not to extend over that portion of the casting 34 which lies under the bottom of a shoe at the rear of the forepart in the pressing operation, and in this location also the casting has a recess 48 therein to insure against contact with a shoe under any conditions. The plate 44 rests on the group of balls 36, as well as upon the upper ends 55 of the pins 38, the balls substantially filling the space within which they are confined but being loose enough to permit them to adjust themselves with the plate 44 to the contour of the bottom of the shoe, after which they serve by their resistance to increase the pressure of the plate on the shoe. The plate 44 has therein a slit 50 (Fig. 4) extending in a direction lengthwise of the shoe substantially midway between the opposite side edges of the plate to increase the flexibility of the plate opposite the ball portion of the shoe, this slit 60 preferably terminating short of that portion of the plate which engages the toe portion of the shoe. Under that portion of the plate 44 which underlies the toe portion of the shoe there is provided, in the construction herein shown, another thin flexible resilient plate 52 to reinforce the plate

44 and thus increase the pressure on the margin of the upper at the toe end of the shoe. The plate 52, which is arranged loosely in contiguous relation to the plate 44, is not supported on the pins 38, but only on the balls 36, and it is provided at one end with a downturned flange 54 (Fig. 5) which lies between the balls 36 and the pins 38 to maintain the plate 52 in proper position. The balls 36 are supported underneath, as in the construction shown in the previously mentioned copending application, by a plurality of leaf springs 56 arranged to extend lengthwise of the shoe in superposed contiguous relation to one another, these springs being secured at the ends thereof which are nearest the toe end of the shoe 15 between the casting 32 and the casting 34, the latter being provided with an opening to receive the springs. The two upper springs 56 are of the same length with their free ends opposite the ball portion of the shoe, but the others decrease progressively in length toward the bottom of the group of springs, this construction serving to increase the yieldability of the portions of the springs which underlie the ball portion of the shoe as compared to the portions underlying the toe of 25 the shoe. Mounted in the casting 34 and extending substantially all the way around the group of balls 36 is an electrical heating unit 58 to which electrical current is supplied through a control box 60 fast on one side of the casting 34. It will be 30 understood that by this means the balls and the plates 44 and 52 are maintained in a heated condition.

The above-described bottom-pressing device 29 is constructed and arranged to receive a shoe 35 placed thereon bottom downward, the pressing plate 44 being inclined somewhat forwardly and downwardly toward the operator's working position to facilitate the presentation of the shoe to the device. After the shoe has been placed on the device it is forced downwardly by means herein-after described to cause the device to apply the required pressure to the margin of the upper. Before the pressure is thus applied the springs 56 are substantially straight, as shown in Fig. 3, 45 and in the pressing operation they yield more or less as illustrated in Fig. 5 while opposing greater resistance to the depression of the plates 44 and 52 under the toe than they do to the depression of the portions of the plate 44 which underlie the ball of the shoe. Relatively greater pressure is accordingly applied to the margin of the upper at the toe portion where comparatively heavy pressure is often needed because of the gathering of the margin over the insole, and the 55 pressure at the toe portion is further increased, as above described, by reason of the fact that the plate 52 underlies the plate 44 in that location. It will be understood, however, that since the plate 52 is loosely mounted under the plate 60 44, so that contiguous portions of the two plates may slip relatively to each other as the plates are flexed in conforming to the contour of the shoe bottom, they conform more readily to the contour than would a single plate of a thickness 65 equal to that of both the plates.

The shoe is forced downwardly to cause the pressing device to apply its pressure to the margin of the upper as above described by a toe rest 61 arranged to engage the shoe on the top of the 70 forepart and preferably long enough to extend somewhat rearwardly of the toe portion of the shoe. This toe rest comprises a hollow flexible member 62 which may be made of rubber and is preferably molded to conform approximately to 75

the lateral contour of the top of the forepart of the shoe, the member 62 serving as a receptacle for material such as sand 64 to permit it to conform more accurately to the contours of shoes of different shapes while nevertheless applying firm pressure to each shoe. The member 62 is clamped by an interior plate 66 and screws 68 to a block 70 movably mounted as hereinafter described on the upper end portion of an arm 72. This upper end portion of the arm is curved laterally and downwardly so that the toe rest occupies a position over the bottom-pressing device 29. The arm 72 is secured to the upper end of a rod 74 which is vertically movable in a bearing 15 in the frame of the machine and is operated by means of substantially the same construction as provided heretofore in machines of the illustrated type for operating a similar rod which carries a shoe holdown member, as disclosed in United States Letters Patent No. 1,120,822, granted on December 15, 1914 upon an application of E. L. Keyes. As therein more fully shown and described, the rod 74 is connected by a link 16 (Fig. 1) to a treadle 18 which is normally held in upright position by a spring 80 and is locked in depressed position by mechanism comprising a pawl 82 arranged to engage ratchet teeth 84 formed on a vertically movable bar 86 connected to the treadle. By depression of the treadle the toe rest 61 is moved downwardly into engagement with the shoe and is operated to press the shoe downwardly upon the pressing device, after which it is maintained by the pawl 82 in position to hold the shoe under pressure as long as desired. To release the shoe the pawl is operated by a pivoted member 88 arranged to be engaged by the knee of the operator and connected to the pawl by a link 90, as more fully disclosed in the last-mentioned Letters Patent.

The present invention provides means for insuring against any loosening of the lasted toe end of the upper by the pressure applied at its margin, this means being so constructed as not only to hold the shoe against any lengthwise displacement in a heelward direction, but also to impart to the shoe a short toeward movement so that the pressing plate 44 has an inward wiping action on the margin of the upper around the end of the toe. The shoe is thus controlled through a heel rest 92 which partially embraces the heel end of the shoe and is provided with a leather facing 94 for engagement with the end face of the upper, the member 92 being secured to the forward ends of two supporting rods 96 which extend lengthwise of the shoe at the opposite sides thereof. The rods 96 are slidingly mounted near their rear ends in sleeve members 98 each of which is pivotally supported on pins 99 carried by a pair of depending arms 100 and 102 (Fig. 7) of a bell-crank lever 104 provided with a forwardly extending arm 106. The two pairs of arms 100 and 102 are connected together by a web 108 (Fig. 2) and are mounted to turn on a rod 110 the intermediate portion of which is supported in an upward extension 112 of the bracket 30. The two sleeve members 98 are connected rigidly together by a cross bar 114. It will thus be evident that when the bell-crank lever 104 is turned in a clockwise direction (Fig. 3) the two sleeve members 98 supported on the depending arms 100 and 102 of the lever are carried rearwardly, i. e., toward the left as the parts are viewed in Fig. 3; and it is through such movement of the members 98 that the rods 96 are operated to impart the lengthwise movement to

the shoe. For this purpose each of the members 98 has pivotally mounted thereon a pawl 116 arranged to engage ratchet teeth 118 on the corresponding rod 96 and controlled as hereinafter described.

The bell-crank lever 104 is operated through downward movement of the shoe-pressing device or unit 29 in response to the pressure of the shoe thereon. For this purpose the casting 32 is vertically movable along guide flanges 120 on the bracket 30 and is connected to the arm 106 of the bell-crank lever 104 by a link 122. A spring 124 seated at its lower end in a socket formed in an arm 125 of the bracket 30 and at its upper end in a socket in the casting 32 yielding resists the downward movement of the pressing device, the spring being held vertical by a pin 126 mounted within it. Upward movement of the pressing device under the influence of the spring 124 is limited by a rod 128 which is threaded at its upper end in the casting 32 and is slidingly mounted in the arm 125, this rod having integral therewith at its lower end a cylindrical plunger 130 which is seated in a corresponding cylindrical recess provided in a member 132 slidingly mounted on the rod and arranged to engage the lower face of the arm 125. Accordingly, the normal height of the pressing device 29 is determined by the rod 128 through the plunger 130 and the member 132, and these parts cooperate also to provide an air check or dash pot for cushioning the upward movement of the pressing device under the influence of the spring 124 when the shoe is released from pressure. A spring 136 bearing at its lower end on a flange 134 formed on the plunger 130 and at its upper end on a shoulder formed on the member 132 causes a relative separating movement of this member and the plunger in the downward movement of the rod 128, the member 132 being held at all times by the spring in contact with the arm 125. By this relative movement of the member 132 and the plunger 130 air is sucked into the interior of the member above the plunger through a passage 138 in the plunger, this passage leading to a ball valve 140 which controls an opening 142 formed in a nipple 144 threaded in the lower end of the plunger. In the upward movement of the pressing device the air trapped between the plunger and the member 132 produces the cushioning effect desired, the plunger fitting loosely enough in the opening in the member 132 to permit the air gradually to leak out around its periphery, since the air cannot escape past the valve 140 which is closed at this time.

When the parts are in their normal positions the pawls 116 are held out of engagement with the ratchet teeth 118 on the rods 96 by arms 146 adjustably secured to the casting 32, as illustrated in Fig. 3, these arms acting on the pawls against the resistance of springs 148 which move the pawls into engagement with the ratchet teeth when the arms are carried downwardly by the casting 32. Accordingly, the rods 96 are initially uncontrolled by the pawls, and at that time they are held in such positions that the heel rest 92 does not interfere with the placing of the shoe upon the pressing plate 44. For this purpose one of the rods 96 has thereon a spring 150 which abuts at one end against the corresponding sleeve member 98 and at the other end against a collar 152 fast on the rod, movements of the two rods under the influence of this spring being limited by the engagement of collars 154 fast

thereon with the rear ends of the sleeve members 98. After mounting the shoe on the pressing plate 44 and forcing the toe rest 61 downwardly by the treadle 78 far enough to engage 5 and clamp the shoe, the operator pushes the heel rest 92 rearwardly into abutting relation to the heel end of the shoe and holds it in that 10 position as he further depresses the treadle. As soon as the pressing device 29 has been forced downwardly with the shoe far enough to release 15 the pawls 116 and permit them to engage the ratchet teeth 118 the operator need no longer hold the heel rest against the shoe. It will be evident that the heel rest is moved rearwardly to 20 a position which will vary in accordance with differences in the lengths of different shoes, and that in whatever position it may be the pawls serve to lock it to the sleeve members 98, after 25 which these members act through the pawls and the rods 96 to impart a short lengthwise movement to the shoe as the pressing device is forced farther downwardly by the pressure of the shoe thereon. In order to increase the final pressure on the shoe there is provided upon the rod 128 30 a spring 156 which is heavier than the spring 124 and is arranged to cooperate with nuts 158 adjustably threaded on the rod to oppose increased resistance to the downward movement of the pressing device. The nuts 158 are spaced 35 from the upper end of the spring 156 a variable distance determined by their adjustment, so that this spring is not effective until near the end of the downward movement of the pressing device after the shoe has been moved lengthwise as required by the heel rest 92. This serves to lessen the amount of work required of the operator in depressing the treadle 78.

In order to hold the heel rest 92 normally at the proper height to operate on the shoe, against the resistance of the force of gravity which tends 40 to swing it downwardly about the axis of the pins 99, there is provided a light spring 160 connected at its upper end to a pin 162 on the cross bar 114 and at its lower end to a pin 164 on the bracket 30. The position in which the heel rest is held by this spring is determined by 45 a stop screw 166 threaded in the cross bar 114 with its lower end in engagement with the bracket 30. It will be evident that by turning 50 this screw the height of the heel rest may be varied. In the short downward movement of the shoe in the pressing operation the heel rest moves with it against the resistance of the light spring 160 by reason of the frictional engagement of the 55 shoe therewith.

In order to facilitate the lengthwise movement of the shoe by the operation of the means above described, the toe rest 61 is so supported and controlled as to permit it to move with the shoe. 60 For this purpose the block 70 is provided with flanges 168 mounted in guideways in the arm 72, so that the block may slide relatively to the arm. The block 70 is controlled by a spring 170 which is compressed as the block moves with the shoe, the spring abutting at one end against an 65 upstanding forked lug 172 on the block. At its other end the spring 170 abuts against an enlarged screw-threaded portion 174 of a rod 176 which extends through the spring and between 70 the arms of the forked lug 172, the portion 174 of the rod being threaded in a plate 178 fast on the arm 72. The normal position of the block 70 relatively to the arm 72 is determined by another forked lug 180 on the block in engagement 75 with one end of the enlarged screw-thread-

ed portion 174 of the rod 176. By means of a knurled hand wheel 182 the rod 176 may be turned to adjust the block 70 and the toe rest in directions lengthwise of the shoe, as may be desirable for operating upon shoes of different 5 sizes or styles.

It will be understood that prior to the operation of the pressing means on the shoe the forepart of the shoe will have been previously lasted. If the pressing means is part of a bed-lasting machine, as herein shown, the operator lasts the toe end of the shoe in the customary manner by use of the toe wipers 16, preferably using adhesive to fasten the upper to the insole. The remainder of the forepart of the shoe at 15 the rear of the toe portion may have been previously lasted, preferably although not necessarily with adhesive, before the shoe comes to this lasting machine, or in case this portion of the shoe has not been lasted, it may be lasted 20 manually while the shoe is on its support in the lasting machine. When the shoe is ready for the bottom-pressing operation the operator presents it bottom downward with its forepart in contact with the pressing plate 44 and then by 25 means of the treadle 78 moves the toe rest 61 into clamping engagement with the top of the forepart of the shoe, as illustrated in Fig. 3. He then pushes the heel rest 92 into abutting relation to the heel-end face of the shoe, and while 30 holding it in that position further depresses the treadle to depress the shoe. As the shoe is forced downwardly the plates 44 and 52 conform themselves to the contour of the shoe bottom, and the 35 balls 36 also adjust themselves to the contour of the shoe with the plates and then by their resistance to the downward movement of the shoe increase the pressure of the plates on the margin of the upper. In the pressing operation the leaf springs 56 yield more or less as illustrated in 40 Fig. 5, and since the portions of the springs which are under the ball portion of the shoe are more yieldable than the portions which are under the toe of the shoe, as well as by reason of the presence of the additional plate 52 under the toe 45 portion of the shoe, relatively greater pressure is applied to the margin of the upper at the toe portion where comparatively heavy pressure is often needed because of the gathering of the margin over the insole. This construction further 50 serves to avoid any undesirable tilting of the shoe by the action of the toe rest thereon if the latter should engage the shoe comparatively near the end of the toe, as might otherwise occur by reason of the fact that the area of the toe portion 55 of the shoe bottom is less than that of the ball portion. As the shoe is pressed against the plate 44 in the manner described the pins 38 may yield more or less in response to the pressure of the plate on their upper ends. In response to 60 the pressure of the shoe thereon the pressing device or unit 29 is forced downwardly against the resistance of the spring 124, and at the beginning of its downward movement it releases the pawls 116 to permit them to engage the 65 ratchet teeth 118 on the rods 96 and thus lock the heel rest in operating position. As the downward movement of the pressing device continues it acts through the pawls to impart a short rearward movement to the heel rest 92 and thus to 70 move the shoe lengthwise along the plate 44, the toe rest moving with the shoe. Substantially at the end of the downward movement of the pressing device the spring 156 becomes operative to oppose increased resistance to the 75

movement and thus to increase the pressure on the shoe. The shoe is left under pressure and under the influence of the heat as long as desired, for example while the operator is lasting another shoe, the toe rest being locked in depressed position by the pawl 82. When it is desired to release the shoe from pressure the operator presses on the member 88, whereupon the arm 72 is lifted by the spring 80, the pressing device is returned to its starting position by the spring 124, and the heel rest is released by the pawls 116 and is returned by the spring 158. The upward movement of the pressing device is retarded or cushioned by the air check 130, 132. It will be understood that when the shoe is released from pressure the plates 44 and 52, the balls 36 and the leaf springs 56 return to their initial positions.

Having described the invention, what I claim as new and desire to secure by Letters Patent of the United States is:

1. In means for pressing the bottoms of shoes, a device for applying pressure and heat to the bottom of the lasted forepart of a shoe before an outsole is applied to the shoe, said device having a heated shoe-pressing portion for engaging and pressing the lasted margin of the upper, means supporting said device in position to receive a shoe carried into contact therewith, means for effecting relative movement of said device and the shoe in a direction heightwise of the shoe to cause the device to press the margin of the upper around the end of the toe and along both sides of the forepart simultaneously, and mechanism 35 for also effecting relative movement of said device and the shoe in a direction lengthwise of the shoe while the pressure is thus being applied simultaneously around the end of the toe and along the sides of the forepart to cause the device 40 to wipe the margin of the upper around the end of the toe in an inward direction.

2. In means for pressing the bottoms of shoes, a device for applying pressure and heat to the bottom of the lasted forepart of a shoe before an outsole is applied to the shoe, said device having a heated shoe-pressing portion arranged to engage and press the lasted margin of the upper, means movable into engagement with the shoe to press it upon said device after the shoe has 45 been placed by the operator with the margin of the upper in engagement with said shoe-pressing portion, and means for effecting relative movement of said device and the shoe in a direction lengthwise of the shoe to cause the device to wipe 55 the margin of the upper around the end of the toe in an inward direction in the pressing operation.

3. In means for pressing the bottoms of shoes, a device for applying pressure and heat to the bottom of the lasted forepart of a shoe before an outsole is applied to the shoe, said device having a heated shoe-pressing portion arranged to engage and press the lasted margin of the upper, means supporting said device in position to receive a shoe placed thereon by the operator, means movable into engagement with the top of the shoe to press it upon the device after the shoe has been placed thereon, and mechanism arranged to act at the heel end of the shoe to impart 65 to the shoe a lengthwise toeward movement in the pressing operation.

4. In means for pressing the bottoms of shoes, a device for applying pressure and heat to the bottom of the lasted forepart of a shoe before an outsole is applied to the shoe, said device hav-

ing a heated shoe-pressing portion arranged to engage and press the lasted margin of the upper, and mechanism arranged to engage the heel-end face of the shoe and to impart to the shoe by such engagement a lengthwise toeward movement 5 to cause said device to wipe the margin of the upper around the end of the toe in an inward direction in the pressing operation.

5. In means for pressing the bottoms of shoes, a device for engaging and pressing the margin 10 of the lasted forepart of a shoe upper overlying an insole, means for effecting relative movement of said device and the shoe in a direction heightwise of the shoe to cause the device to press the margin of the upper, and mechanism arranged 15 to act in response to the application of the pressure to the shoe to effect relative movement of said device and the shoe in a direction lengthwise of the shoe to cause the device to wipe the margin of the upper around the end of the toe in a direction inwardly from the edge of the insole.

6. In means for pressing the bottoms of shoes, a device for engaging and pressing the margin 20 of the lasted forepart of a shoe upper overlying an insole, means for effecting relative movement 25 of said device and the shoe in a direction heightwise of the shoe to cause the device to press the margin of the upper, a heel rest for engaging the heel-end face of the shoe, and mechanism arranged to act in response to the application of 30 the pressure to the shoe to impart to the shoe through said heel rest a lengthwise movement in the pressing operation.

7. In means for pressing the bottoms of shoes, a device for engaging and pressing the margin 35 of the lasted forepart of a shoe upper overlying an insole, means for pressing the shoe upon said device, said pressing device being movable in response to the pressure of the shoe thereon, and mechanism arranged to be operated by such 40 movement of the pressing device to effect relative movement of the device and the shoe in a direction lengthwise of the shoe in the pressing operation.

8. In means for pressing the bottoms of shoes, 45 a device for engaging and pressing the margin of the lasted forepart of a shoe upper overlying an insole, means for pressing the shoe upon said device, said pressing device being movable in response to the pressure of the shoe thereon, a 50 heel rest movable into engagement with the heel-end face of the shoe after the shoe has been presented in engagement with said device, and mechanism operative in response to the movement of said pressing device for locking said heel rest in 55 shoe-engaging position.

9. In means for pressing the bottoms of shoes, a device for engaging and pressing the margin 60 of the lasted forepart of a shoe upper overlying an insole, means for pressing the shoe upon said device, said pressing device being movable in response to the pressure of the shoe thereon, a 65 heel rest for engaging the heel-end face of the shoe, and mechanism arranged to act on said heel rest in response to the movement of the pressing device to impart to the shoe a lengthwise movement in the pressing operation.

10. In means for pressing the bottoms of shoes, a device for engaging and pressing the bottom 70 of the forepart of a shoe after lasting but before an outsole is applied to the shoe, a heel rest movable into engagement with the heel-end face of the shoe after the shoe has been presented in engagement with said pressing device, and mechanism for operating said heel rest to im- 75

part to the shoe a lengthwise movement in the pressing operation.

11. In means for pressing the bottoms of shoes, a device for engaging and pressing the bottom of the forepart of a shoe after lasting but before an outsole is applied to the shoe, a toe rest movable into engagement with the top of the forepart of the shoe after the shoe has been placed on said device and further movable to 10 press the shoe upon the device, a heel rest arranged to engage the heel-end face of the shoe, and means for operating said heel rest to impart to the shoe a lengthwise toeward movement in the course of the movement of the toe rest to 15 press the shoe upon the device.

12. In means for pressing the bottoms of shoes, a device for engaging and pressing the bottom of the forepart of a shoe after lasting but before an outsole is applied to the shoe, a toe rest 20 arranged to engage the shoe at the top of the forepart and movable to press the shoe upon said device, the device being yieldingly movable in response to the pressure of the shoe thereon, a heel rest arranged to engage the heel-end face 25 of the shoe, and mechanism controlled by the movement of said device for operating the heel rest to impart to the shoe a lengthwise toeward movement in the pressing operation.

13. In means for pressing the bottoms of shoes, 30 a device for engaging and pressing the bottom of the forepart of a shoe after lasting but before an outsole is applied to the shoe, means for pressing the shoe upon said device, the device being yieldingly movable in response to the pressure of the shoe thereon, a heel rest arranged to engage the heel-end face of the shoe, a support 35 for said heel rest movable in directions lengthwise of the shoe to permit the heel rest to be moved into engagement with the shoe by 40 the operator, said support having teeth thereon, and mechanism arranged to be operated by the movement of said pressing device for engaging said teeth and operating the heel rest to impart to the shoe a lengthwise toeward movement in 45 the pressing operation.

14. In means for pressing the bottoms of shoes, a device for engaging and pressing the bottom of the forepart of a shoe after lasting but before an outsole is applied to the shoe, means for 50 pressing the shoe upon said device, the device being movable in response to the pressure of the shoe thereon, mechanism arranged to be operated by the movement of the pressing device to impart to the shoe a lengthwise movement in the pressing operation, a spring for yieldingly resisting the movement of the pressing device, and another spring arranged to become operative 55 in the course of the movement of the pressing

device to oppose increased resistance to such movement.

15. In a machine for pressing the bottoms of shoes, a device for engaging and pressing the bottom of the forepart of a shoe after lasting 5 but before an outsole is applied to the shoe, a toe rest arranged to engage the shoe at the top of the forepart, means for effecting relative movement of said device and toe rest to cause the device to press the shoe, and mechanism for 10 moving the shoe lengthwise relatively to the pressing device in the pressing operation, said toe rest being so mounted as to permit it to move in a direction lengthwise of the shoe in response to action of the shoe thereon as the shoe receives 15 its lengthwise movement.

16. In means for pressing the bottoms of shoes, a device for engaging and pressing the bottom of the forepart of a shoe after lasting but before an outsole is applied to the shoe, a toe rest 20 arranged to engage the shoe at the top of the forepart, an arm supporting said toe rest and movable to cause the toe rest to press the shoe upon said device, a heel rest arranged to engage the heel-end face of the shoe, and means for 25 operating said heel rest to impart to the shoe a lengthwise toeward movement in the pressing operation, said toe rest being slidably mounted on its supporting arm to permit it to partake of the lengthwise movement of the shoe. 30

17. In means for pressing the bottoms of shoes, a device for pressing the bottom of the forepart of a shoe after lasting but before an outsole is applied to the shoe, said device comprising a shoe-engaging plate arranged to engage the bottom of the shoe at the toe and ball portions and flexibly conformable to the contour of the shoe in response to pressure of the shoe thereon, and another flexible plate arranged to reinforce 35 said first-named plate in a location opposite the toe portion only of the shoe bottom. 40

18. In means for pressing the bottoms of shoes, a device for pressing the bottom of the forepart of a shoe after lasting but before an outsole is applied to the shoe, said device comprising a 45 metallic shoe-engaging plate arranged to engage the bottom of the shoe at the toe and ball portions and flexibly conformable to the contour of the shoe in response to pressure of the shoe thereon, a group of metal balls arranged to adjust 50 themselves to the contour of the shoe with said plate and thereafter to increase the pressure of the plate on the shoe, and another flexible metallic plate loosely mounted between said first-named plate and the group of balls in a location 55 opposite the toe portion only of the shoe.

CHARLES H. PEPIN.
